CONFECTION MACHINE

William J. Taylor, Syracuse, N. Y., assignor to
The Lamson Company, Syracuse, N. Y., a corporation of Massachusetts

Application June 23, 1936, Serial No. 86,719

18 Claims. (Cl. 107—29)

This invention relates to an improvement in a confection machine of the general type illustrated and described in the patent to Robb No. 1,960,456, dated May 29, 1934, and more particularly to a filling unit usable therein.

The objects of the present invention are to provide in a filling unit usable in a confection machine, means for moving the unit in unison with the molds to be filled and for discharging fluid or semi-viscous material while the unit is so moving; means for measuring the quantities of such material; means for preventing the waste of any such material through dripping after the material has been discharged; and instrumentalities capable by structure and operation of carrying out the purposes of such unit all as will appear from a consideration of the following description and of the drawings which form a part thereof and in which

20 Fig. 1 is a view in side elevation of a filling unit embodying this invention shown in relation to a portion of the conveyor carrying the molds to be filled;

Fig. 2 is an enlarged side elevation of a portion of the unit partly in section and of the mold conveyor illustrating the filling operation;

Fig. 3 is a detail view of a portion of the filling mechanism while in the replenishing operation;

30 Fig. 4 is a plan view of the filling unit with the cover removed;

Fig. 5 is a front elevation thereof with the cover removed together with a mold carrier;

Fig. 6 is an enlarged sectional view taken along the line 6—6 on Fig. 2;

Fig. 7 is an enlarged end elevation of the plunger operating mechanism, with portions of the structure removed;

40 Fig. 8 is an enlarged cross sectional view of a filling nozzle; and

Fig. 9 is a diagrammatic view illustrating the relative movement of the filling nozzles and the mold carriers.

The filling unit 10 comprises a tank 11 pivotally suspended from a shaft 12 over a mold conveyor here shown as similar to that disclosed in copending application Serial No. 54,166, filed December 23, 1935. The mold conveyor comprises a pair of chains 15 which pass around a plurality of sprockets 16 and 17 and between which are carried a plurality of mold carriers 18. The shaft 12 and sprockets 16 and 17 are suitably supported in a frame 19. The tank 11 is suspended from the shaft 12 by end plates 20 and is oscillated thereon by means of a stub shaft 21

through a disk 22 carried thereby and a link 23 secured at one end to the disk 22 and at the other end to an ear 24 on one of the end plates 20.

The mold conveyor is continuously driven by means not shown. The shaft 12 is driven from the shaft 25 of one pair of sprockets 16 through bevel gears 26 and 27, a vertically inclined shaft 28 and bevel gears 29 and 30. The shaft 21 is driven from the shaft 12 through bevel gears 31 and 32, a vertically inclined shaft 33 and bevel gears 34 and 35. The shafts 12 and 21 thus rotate in unison with the travel of the mold conveyor.

The end walls 20 of the tank are connected by a front angle bar 36 and a rear angle bar 37. The end walls and angle bars support the walls which with the bottom plate 38 form a hopper 39 for the fluid or semi-viscous material with which the molds are to be filled. The front wall 40 and the end walls 41 and 42 are vertical while the rear wall 43 is inclined. The walls of the hopper are suitably insulated to prevent evaporation of the contents of the hopper and the formation of condensation on the outer surfaces. As here shown this insulation is attained by means of cork sheets 44 held in contact with the outer faces of the walls 40 and 43 of the hopper and the end walls 20 of the tank by a casing 45. Other insulating means may be substituted therefor if desired.

Mounted in recesses 46 in the bottom plate 38 are filling cylinders 47. These cylinders are equal in number to the molds of the mold carriers and are arranged in a row extending across the machine parallel to the front wall 40. Each cylinder registers with a mold of each mold carrier as indicated on Fig. 5. The upper end of each cylinder enters a recess 48 in a plate 49 projecting from the front angle bar 36 (see Fig. 7). The recess 48 is an annular enlargement of an opening 50 which preferably is of the same internal dimension as the interior of the cylinder. In assembling the cylinders in the tank the lower ends are seated in the recesses 46 of the bottom plate and then, the upper ends being inserted in the recesses 48 of the plate 49, the plates are fixed to the bar 36 to secure the cylinders in place. Pairs of dowels 51 are here provided to position the plates initially and the cylinders are clamped in position by the bolts 52. The plates thus hold the cylinders in place and seat them firmly in the recesses so that any entry to the cylinders of the material in the hopper through the recesses 46 is prevented. Recipro-

cable in each cylinder 47 is a plunger or piston 55, and a bar 56 pivoted in a recess 57 at the upper end of the plunger. The plungers are reciprocated by arms 58 fixed to a rock shaft 59 supported in the end walls 20. The free end of each arm 58 carries a cross pin 60. The ends of the pins project at opposite sides of the arm and the upper ends of the bars 56 are slipped over the projecting ends of the pins and suitably secured in place as by cotter pins 61. One end of the rock shaft 59 projects beyond the tank 11 and on it is mounted an arm 62. The shaft 59 is actuated by the shaft 12 through the arm 62, an adjustable link 63, an adjustable block 64 and a disk 65 fixed upon the end of the shaft 12 (see Fig. 7). The block 64 is supported in a pocket 66 extending diametrically across one face of the disk 65 and its position in the pocket may be adjusted by means of a screw 67 to regulate the amount of movement imparted to the shaft 59. The shaft movement may be further regulated by means of the adjustable link 63.

The bottom plate 38 has in its under face a recess 70 closed by a plate 71 which extends across the mouth of the recess and is secured in any suitable manner to the under face of the plate. The recess 70 is connected by passages 72 to the hopper 39 and by passages 73 to the interior of the filling cylinders 47. Each passage 72 is in longitudinal alignment with a passage 73. Nozzles 74 are carried by the plate 71 in vertical alignment with the passages 73 and lead from the recess 70. Mounted to reciprocate longitudinally in the recess 70 is a slide valve 75 having a plurality of passages 76 therethrough and a plurality of transversely extending recesses 77 in the upper face thereof. The recesses 77 are of such length that, as shown in Fig. 3, they will connect the passages 72 and 73 in one position of the slide. The passages 76 and recesses 77 are alternately arranged longitudinally of the valve 75 and are spaced apart the same distances as are the passages 72 or 73. When the valve 75 is at one limit of its movement, the right in Fig. 6, each passage 76 registers with and connects a passage 73 and the nozzle 74 in alignment therewith (Fig. 2). When the valve 75 is at the other limit of its movement, the left in Fig. 6, each recess 77 registers with and connects a passage 72 and the aligned passage 73 (Fig. 3).

Reciprocation is imparted to the slide valve 75 by bell crank levers 80 pivotally mounted on ears 81 projecting from the outer faces of the end plates 20. The levers 80 are actuated by cams 82 on the shaft 12 through rollers 83 at the upper ends of blocks 84 slidably in pockets 85 formed on the end plates and adjustable links 86 pivotally secured at their ends to the levers 80 and the blocks 85. The cams 82 are identical in form the periphery of each being formed by two arcuate sections 87 and 88 of substantially the same length connected at the ends by reverse curved sections 89 (see Fig. 2). As indicated in the drawings the cams are so positioned on the shaft that when one roller 83 is in contact with the section 87 of one cam the other roller 83 is in contact with the section 88 of the other cam and that both rollers 83 contact simultaneously with the reversed curved sections 89 of the cams. The lever at the left (Fig. 5) moves the valve to the position shown in Figs. 2 and 6 and the lever at the right (Fig. 5) moves the valve to the position shown in Fig. 3. Both levers are at all times in contact with the valve and coact to control its movement. The travel of the valve 75 in both directions is limited by suitable stop means as for example by pins 90,

one only of such means being here shown (see Fig. 6).

The nozzles 74 are formed to prevent dripping or dribbling, see particularly Figs. 6 and 8. The passage 91 through the nozzle is tapered downwardly, the mouth being slightly larger than the outlet of the valve passage 76 and the outlet being slightly smaller. The outer surface of the nozzle is faced back to provide a thin blade-like annular flange 92 defining the outlet. The edge of the flange is sharp and when, as will be described later, the flow through the nozzles is cut off, the passages are substantially cleared by gravity and any material left forms a bubble which remains intact and is not shaken off by the movement of the valve.

As further protection for the material in the hopper 39 the top of the tank may be closed by a cover 100 made up of a stationary section 101 and a movable section 102 hinged to the stationary section. The stationary section comprises a plate 103 having slots 104 which receive the bars 56, and bolts 52 and a cross strap 105, the ends 106 of which are upturned and provided with notches 107. Bolts 108 projecting from bosses 109 on the end plates 20 of the tank enter the notches 107 when the cover is mounted on the tank. The slotted portions of the plate 103 rest on the plates 49 and the section 101 is secured in place by the heads of the bolts 52. A crossbar 110 fixed to the plate 103 below the strap 105 rests on the upper edges of the end walls 41.

The movable section 102 is joined to the stationary section 101 by a plurality of leaf hinges 111 and comprises a plate 112 reinforced at its side edges by flanges 113. The under face of the plate 112 is suitably insulated as by cork 114 enclosed between plates 115 to further prevent the loss of moisture by evaporation and to prevent the formation of condensation on the movable section of the cover.

The operation of the filling machine is in unison with the travel of the mold conveyor, the shaft 12 which, as pointed out above, controls the movement of the various movable elements, being driven from the shaft 25. Referring to Fig. 1, the cylinders 47 are filled as the tank swings to the left and are discharged to fill the molds as the tank swings to the right. The distance traveled by the tank is preferably regulated so that as shown in Fig. 9 the center line of a row of nozzles is slightly in advance of the center line of a row of mold carriers at the limit of the swing designated by 95 where the cylinder filling stops and the mold filling starts; is in register therewith at 55 the middle of either operation and is slightly behind the center line of the mold carriers at the limit designated by 96 where the cylinder filling starts and the mold filling stops.

Assuming that a row of nozzles is at the position 95 on Fig. 9 the disk 65 on the shaft 12 starts to depress the pistons 55 through the link 63, arm 62, shaft 59, arms 58 and bars 56, and at the same time the cams 82 on the shaft 12 coact to shift the slide valve 75 to the right into the position shown in Fig. 6. The movement imparted by the disk 65 to the pistons 55 continues until the row of nozzles takes the position 96, being slower at the beginning and end than elsewhere. The cams 82, however, are so formed that as the position 95 is reached the slide valve is opened quickly by moving the valve to the right and as the position 96 is reached is quickly closed by moving the valve to the left. The valve is at rest during the travel of the tank in either direction. The movements 70

of the valve are caused by the contact of the reverse curved sections of the cam with the rollers 83. During the travel of the tank in either direction the rollers 83 are in contact with the arcuate sections and no movement of the valve is set up thereby.

As the tank swings to the left from the position 96 the pistons 55 are raised first slowly, then more rapidly and finally slowly again. 10 The slide valve 75 is, as pointed out above, closed and in the position shown in Fig. 3 so that the material in the hopper flows through the passages 77 into the filling cylinders 47 and fills the spaces left below the pistons 55 as they 15 are raised. As the tank swings to the right the pistons are lowered and since the valve is open the contents thereof are discharged into the molds with which they at that time travel in register. 20 The position indicated by full lines in Fig. 1 and shown on a larger scale in Figs. 2, 3, 6 and 7 is that taken by the tank and its associated elements when the center line of the row of nozzles is in register with the center line of a row of 25 mold carriers as shown in Fig. 9.

At that position the pistons 55 are half way between the upper and lower limits of their travel whether the nozzles be traveling to the left or to the right, and the slide valve is at rest being 30 however, in the position shown in Figs. 2 and 6 if the nozzles are traveling to the right and in the position shown in Fig. 3 if the nozzles are traveling to the left.

While one embodiment of this invention has 35 been shown and described it will be understood that the invention is not limited thereto and that other embodiments may be made without departing from the spirit and scope of the invention as set forth in the following claims.

40 I claim:

1. In a confection machine including a conveyor, a plurality of mold carriers transported thereby and means for advancing said conveyor continuously, a filling unit comprising a tank pivotally supported above the conveyor and adapted to oscillate longitudinally thereof, said tank including a hopper, a plurality of filling cylinders therein, a plurality of filling nozzles in alignment with said cylinders, plungers in said cylinders, movable valve mechanism which in one position connects the cylinders with the hopper and in another position connects the cylinders with the nozzles and means for actuating said pistons and valve mechanism in timed relation, the pistons being raised when the valve mechanism is in the position to connect the hopper and cylinders and lowered when the valve mechanism is in the position to connect the cylinders and nozzles, and means for oscillating said tank whereby the nozzles, during part of the movement of the tank, travel in register with a mold carrier on the conveyor at which time the nozzles are connected with the cylinders, the pistons thereof are lowered and the molds of the carrier are filled.

2. In a confection machine including a conveyor, a plurality of mold carriers transported thereby and means for advancing said conveyor continuously, a filling unit comprising a tank pivotally supported above the conveyor and adapted to oscillate longitudinally thereof, said tank including a hopper, a plurality of filling cylinders therein, a plurality of filling nozzles in alignment with said cylinders, plungers in said

cylinders, movable valve mechanism which in one position connects the cylinders with the hopper and in another position connects the cylinders with the nozzles and means for actuating said pistons and valve mechanism in timed relation, the pistons being raised when the valve mechanism is in the position to connect the hopper and cylinders and lowered when the valve mechanism is in the position to connect the cylinders and nozzles, and means for oscillating said tank which means include a shaft driven by the conveyor advancing means, whereby the nozzles, during a part of the movement of the tank, travel in register with a mold carrier at which time they are connected with the cylinders, the pistons of the cylinders are lowered and the molds of the carrier are filled.

3. In a confection machine including a conveyor, a plurality of mold carriers transported thereby and means for advancing said conveyor continuously, a filling unit comprising a tank pivotally supported above the conveyor and adapted to oscillate longitudinally thereof, said tank including a hopper, a plurality of filling cylinders therein, a plurality of filling nozzles in alignment with said cylinders, plungers in said cylinders, movable valve mechanism which in one position connects the cylinders with the hopper and in another position connects the cylinders with the nozzles and means for actuating said pistons and valve mechanism in timed relation, the pistons being raised when the valve mechanism is in the position to connect the hopper and cylinders and lowered when the valve mechanism is in the position to connect the cylinders and nozzles, a shaft driven by the conveyor advancing means, and means actuated by said shaft for oscillating the tank, reciprocating said pistons and operating said valve mechanism whereby the tank is oscillated and the nozzles, during part of the movement of the tank, travel in register with a mold carrier, at which time the nozzles are connected by the valve mechanism to the cylinders the pistons of the cylinders are lowered and the molds of the carrier are filled.

4. In a confection machine including a conveyor, a plurality of mold carriers transported thereby and means for advancing said conveyor, a filling unit comprising a tank pivotally supported above the conveyor and adapted to oscillate longitudinally thereof, the movement of the tank in one direction being in unison with the movement of the carriers, a shaft on which said tank is supported, means rotating said shaft from the conveyor advancing means and means actuated by said shaft for oscillating said tank.

5. In a confection machine including a conveyor, a plurality of mold carriers transported thereby and means for advancing said conveyor, a filling unit comprising a tank pivotally supported above the conveyor and adapted to oscillate longitudinally thereof, the movement of the tank in one direction being in unison with the movement of the carriers, a shaft on which said tank is supported, means rotating said shaft from the conveyor advancing means and means actuated by said shaft for oscillating said tank, said last named means comprising a shaft driven from said first named shaft, a disk on said second named shaft and an arm of which one end is connected to said tank and the other end is connected to said disk off-center thereof.

6. In a confection machine including a conveyor, a plurality of mold carriers transported

- thereby and means for advancing said conveyor, a filling unit comprising a tank pivotally supported above the conveyor and adapted to oscillate longitudinally thereof, the movement of the tank in one direction being in unison with the movement of the carriers, a shaft on which said tank is supported, means rotating said shaft from the conveyor advancing means, means for oscillating said tank, nozzles in said tank, valve mechanism which allows fluid material in the tank to flow through the nozzles into the molds of the carriers when the tank is moved in unison with the carriers and means actuated by said shaft for operating said valve mechanism.
15. 7. In a confection machine including a conveyor, a plurality of mold carriers transported thereby and means for advancing said conveyor, a filling unit comprising a tank pivotally supported above the conveyor and adapted to oscillate longitudinally thereof, the movement of the tank in one direction being in unison with the movement of the carriers, a shaft on which said tank is supported, means rotating said shaft from the conveyor advancing means, means for oscillating said tank, nozzles in said tank, valve mechanism which allows material in the tank to flow through the nozzles into the molds of the carriers when the tank is moved in unison with the molds and means actuated by said shaft for operating said tank oscillating means and said valve mechanism.
8. In a confection machine including a conveyor, a plurality of mold carriers transported thereby and means for advancing said conveyor, a filling unit comprising a tank pivotally supported above the conveyor and adapted to oscillate longitudinally thereof, the movement of the tank in one direction being in unison with the movement of the carriers, a shaft on which said tank is supported, means rotating said shaft from the conveyor advancing means, means for oscillating said tank, nozzles in said tank, filling cylinders mounted in said tank in register with said nozzles, movable valve mechanism which in one position admits fluid material in the tank into the filling cylinders and in another position allows the material in the cylinders to flow through the nozzles into the molds of the carriers as the tank moves in unison with the carriers and means for operating said valve mechanism.
50. 9. In a confection machine including a conveyor, a plurality of mold carriers transported thereby and means for advancing said conveyor, a filling unit comprising a tank pivotally supported above the conveyor and adapted to oscillate longitudinally thereof, the movement of the tank in one direction being in unison with the movement of the carriers, a shaft on which said tank is supported, means rotating said shaft from the conveyor advancing means, means for oscillating said tank, nozzles in said tank, filling cylinders mounted in said tank in register with said nozzles, movable valve mechanism which in one position admits fluid material in the tank into the filling cylinders and in another position allows the material in the cylinders to flow through the nozzles into the molds of the carriers as the tank moves in unison with the carriers and means for operating said valve mechanism, said means for oscillating the tank and said means for operating the valve mechanism being actuated by the shaft on which the tank is pivotally supported.
10. In a confection machine including a conveyor, a plurality of mold carriers transported thereby and means for advancing said conveyor,

a filling unit comprising a tank pivotally supported above the conveyor and adapted to oscillate longitudinally thereof, the movement of the tank in one direction being in unison with the movement of the carriers, a shaft on which said tank is supported, means rotating said shaft from the conveyor advancing means, means for oscillating said tank, nozzles in said tank, filling cylinders mounted in said tank in register with said nozzles, pistons reciprocable in said cylinders, means for actuating said pistons, movable valve mechanism which in one position admits fluid material in the tank into the filling cylinders and in another position allows the material to flow from the cylinders through the nozzles into the molds of the carriers as the tank moves in unison with the carriers, and means for operating said valve mechanism, said means for oscillating the tank, actuating the pistons and operating the valve mechanism being actuated by the shaft on which the tank is pivotally supported.

11. In a confection machine including a conveyor, a plurality of mold carriers transported thereby and means for advancing said conveyor, a filling unit comprising a tank, filling cylinders mounted in said tank, pistons reciprocable in said cylinders, means for reciprocating said pistons, nozzles on said tank in register with said cylinders, a reciprocable slide valve having transversely extending recesses in the upper face thereof, and passages therethrough, said recesses and passages being so positioned that at one limit of movement of the valve the recesses register with the cylinders and at the other limit the passages register with the cylinders and the nozzles, and means for reciprocating said valve, the reciprocations of the pistons and valve being so timed that when the pistons are moving upwardly the recesses register with the cylinders and when the pistons are moving downwardly the passages register with the cylinders and nozzles.

12. In a confection machine including a conveyor, a plurality of mold carriers transported thereby and means for advancing said conveyor, a filling unit comprising a tank, filling cylinders mounted in said tank, pistons reciprocable in said cylinders, means for reciprocating said pistons, nozzles on said tank in register with said cylinders, a reciprocable slide valve having transversely extending recesses in the upper face thereof, and passages therethrough, said recesses and passages being so positioned that at one limit of movement of the valve the recesses register with the cylinders and at the other limit the passages register with the cylinders and the nozzles, means for reciprocating said valve, and means actuated by said conveyor advancing means for operating said piston and valve reciprocating means in timed relation so that when the pistons are moving upwardly the recesses register with the cylinders and when the pistons are moving downwardly the passages register with the cylinders and nozzles.

13. Means for filling molds transported by a conveyor while in transit, comprising a tank mounted to oscillate longitudinally of the conveyor and having nozzles which travel in substantial register with the molds as the tank is oscillated in one direction, means for oscillating said tank and means for causing fluid material in the tank to flow through the nozzles into the molds during the oscillation of the tank in that direction only.

14. Means for filling molds transported by a conveyor while in transit, comprising a tank

- 5 mounted to oscillate longitudinally of the conveyor and having nozzles which travel in substantial register with the molds as the tank is oscillated in one direction, means for oscillating said tank, means for measuring predetermined quantities of fluid material and means for causing such quantities to flow through the nozzles into the molds during the oscillation of the tank in that direction only.
- 10 15. Means for filling molds transported by a conveyor while in transit comprising a tank mounted to oscillate longitudinally of the conveyor and having nozzles which travel in substantial register with the molds as the tank is oscillated in one direction, means for oscillating said tank, means for measuring predetermined quantities of fluid material, means for causing such quantities to flow through the nozzles into the molds during the oscillation of the tank in that direction and means for actuating said measuring means during the remainder of the oscillation of the tank.
- 15 20. Means for filling molds transported by a conveyor while in transit comprising a tank mounted to oscillate longitudinally of the conveyor and having nozzles which travel in substantial register with the molds as the tank is oscillated in one direction, means for oscillating said tank, means for measuring predetermined quantities of fluid material and valve mechanism con-

trolling the flow of the quantities of material from such measuring means through the nozzles into the molds during the oscillation of the tank in that direction and the supply of material to such measuring means at another time.

17. Means for filling molds transported by a conveyor while in transit comprising a tank mounted to oscillate longitudinally of the conveyor and having nozzles which travel in substantial register with the molds as the tank is oscillated in one direction, means for oscillating said tank, means for measuring quantities of fluid material, movable valve mechanism which in one position permits the supply of material to such measuring means and in another position permits the flow of the measured quantities from the measuring means through the nozzles into the molds during the oscillation of the tank in the direction in which the nozzles travel in substantial register with the molds and means for actuating said valve mechanism.

18. A delivery nozzle for use in machines of the class described, said nozzle having a bore which converges downwardly toward its delivery end, the inner wall of the bore being extended beyond the delivery end of the nozzle proper to form a thin blade-like annular edge whereby dripping is prevented after the normal flow of material through the nozzle has terminated.

WILLIAM J. TAYLOR. 30
